UNITED STATES PATENT OFFICE

2,480,573

COOLING APPARATUS

Warren S. Hall, Chicago, Ill., assignor to Carnegie-Illinois Steel Corporation, a corporation of New Jersey

Application September 20, 1946, Serial No. 698,262

3 Claims. (Cl. 266—2)

1

This invention relates to a cooling apparatus for articles which have been heat treated, and particularly the ends of railroad rails, although not limited thereto.

In the operation of railroads, particularly along main lines which accommodate heavy locomotives moving at high rates of speed, the rails of the railroad tracks are subjected to very heavy impact. This impact is particularly heavy at the joints between adjacent rail ends, where, due to the appreciable deflection of the tracks, the impact or hammering action is greater.

It has been proposed to harden the steel of the rail ends by heating the same above the upper critical temperature thereof, and then rapidly cooling to a temperature which is below the lower critical temperature; all in accordance with well known metallurgical practice. The heating of the ends of the rails is easily accomplished, but satisfactory cooling is very difficult to achieve.

Heretofore, various means for cooling rail ends have been tried but they have not, so far as I am aware, proved entirely satisfactory. This is of course due to the fact that they do not provide the necessary uniformly controlled cooling.

It is among the objects of the present invention to provide an efficient cooling apparatus, which may be used for cooling the ends of heat-treated railroad rails and the like.

Another object is the provision of a device of the class described which is readily portable, cheap and easy to manufacture, operate and maintain; and one which is at the same time very durable in service.

The invention, then, comprises the features hereinafter described and as particularly pointed out in the claims, the following description and the annexed drawings setting forth in detail certain illustrative embodiments of the invention, these being indicative of several of the number of ways in which the principles of the invention may be employed.

In said drawings:

Figure 1 is an elevational view, partly in section, illustrating the cooling apparatus of the present invention;

Figure 2 is a sectional view on the line II—II of Figure 1; and

Figure 3 is a diagrammatic perspective illustrating the mechanical movement relied upon to effect the operation of the elements of the apparatus.

Referring more particularly to the drawings, the apparatus of the present invention provides a substantially flat hollow member 2 which is

2

adapted to lie upon the head of a railroad rail and extend for a short distance toward the middle thereof. As shown more clearly in Figure 2, the hollow member 2 is substantially rectangular in cross-section and provided with suitable coolant channels, as shown at 3. The bottom of the substantially flat hollow member 2 is recessed, as at 5, to conform to the top and adjoining edges of the head of the rail to be heat-treated.

10 Referring to Figure 1, the inner end of the hollow member 2 is closed, as shown at 6, while the outer end thereof is provided with an integrally-formed downwardly depending hollow member 7 which extends for the full depth of the end of the rail and is widened out towards its bottom, as shown in Figure 2. The hollow member 7 communicates with a rearward extension 10 which takes the form of a hollow handle. Suitable passageways and restrictions are provided 15 for obtaining an efficient flow of coolant through the hollow member 7 and the coolant channels 3 of the hollow member 2, but as such form no part 20 of the present invention.

25 From the foregoing construction and arrangement it will be perceived that the elements defining the hollow member 2 and the hollow member 7 may be so shaped as to provide comparatively close contact with the top surface (and adjoining portions of the side edges) of the rail head as well as the entire surface of the extremity of the rail. By making these members of copper or other material having high heat conductivity and cooling the same with water, or other suitable coolant, heat may be conducted away from these contacted areas in a highly efficient and uniform manner, thereby securing the desired metallurgical effect. But this does not include the major portion of the sides of the rail head as well as the web of the rail. However, the present invention 30 also seeks to provide means for cooling these portions as well, and for this purpose there is provided a pair of relatively movable hollow side castings, generally indicated at 16, which are adapted to be supported by, and to depend from, the sides of the hollow member 2. More specifically, each of these hollow side castings 16 35 comprises a pair of spaced and generally conforming plates, the inner of which provides a cooling surface defined by a vertical member 18 which depends downwardly in parallelism with the side face of the hollow member 2, an inwardly extending horizontal member 19 which extends inwardly under the overhanging edge of the aforesaid hollow member, a downwardly depending member 20 40 which extends the remainder of the depth of the

55 which extends the remainder of the depth of the

side wall of the head of the rail, an inwardly sloping wall 21 which extends inwardly toward the web of the rail, and a downwardly depending member 22 which extends in parallelism for a substantial portion of the depth of the aforesaid web. Each of these castings 16 is provided with an inwardly extending continuous flange 23 which is adapted to lie upon and slide on the adjacent portion of the top of hollow member 2.

On the top of each of the hollow side castings 16 there are a pair of widely spaced vertically extending lugs 30 which connect with an integrally formed bar 32 which extends longitudinally of the hollow member 2 to overlie the rearward extension 10 on the hollow vertical member 7. Each of the lugs 30 is embraced by a pair of ears 33 which are integrally formed on the top of the horizontal hollow member 2, and each of the aforesaid lugs 30 is provided with a horizontally extending slot 34. Each of the slots 34 carries a pin 36 which extends therethrough and projects from either side thereof to seat in the adjacent ear. From the foregoing construction and arrangement it will be perceived that the bars 32 which are superposed on, and formed integrally with, the hollow side castings 16, may be moved inwardly and outwardly with respect to each other in a horizontal plane. Thus, the horizontal hollow member 2 may be so constructed that its bottom will fit rails of widely varying sizes, except that it will, of course, project laterally from each side of the head of a rail of smaller size. The inner surfaces of the hollow side castings 16, adjacent the side edges of the horizontal hollow member 2 in effect provide longitudinal slots which act as guides so that by lateral movement of the said hollow side castings 16 they will contact the sides of the head of a rail of any size, and the inner surface of the vertical hollow member 7 will contact the entire end surface of a rail of any size. So far as the hollow side castings 16 are concerned, those portions thereof which do not contact the web of the rail, i. e. the walls 22, provide excellent means for absorbing the radiant heat therefrom. Water or other coolant may be applied to the hollow members in any convenient manner.

In applying the apparatus to the end of a rail of any size it has been necessary to move the hollow side castings 16 away from each other for a sufficient time to permit of the insertion of the device around the end of the rail, at which time the said castings 16 are moved together as far as possible to permit of a contact of the outside faces of the inner walls 20 thereof with the side faces of the head of the rail.

It will be understood by those skilled in the art that various means may be utilized for moving the castings 16 toward and away from each other. However, I have illustrated in the drawings a lever system which has proved to be effective, and the same will be described immediately hereinafter.

Referring to Figure 1 of the drawings, there is mounted on the upper portion of the rearward extension 10 forming the hollow handle a bell crank lever 40. Immediately below the bell crank lever 40 there is pivotally mounted a vertically extended hand-operated lever 41 which is connected on its free end to one lever of the bell crank lever 40. The inward motion of the pivotally mounted lever 41 is resisted by a spring 42.

To the upper lever of the bell crank lever 40 there is pivotally connected a link 44, to the upper end of which there is connected a pair of divergent toggle links 45. The outer ends of the

toggle links 45 are connected to the lower levers of a pair of vertically extending tongs 47.

Disposed atop the apparatus of the present invention and extending between the longitudinally extending parallel bars 32 is a pair of horizontal tongs 49, the outer ends of which are pivotally connected to the upper ends of the vertical tongs 47. Connected to the inner ends of the horizontal tongs 49 are a pair of links 51 which extend crosswise of the said tongs 49, and each of these links 51 is pivotally connected on its extending end to the oppositely disposed bar 32. A spring 53 extends between and is connected to the bars 32 for the purpose of resiliently maintaining the latter in their innermost positions.

When the rearward extension 10 forming the hollow handle is squeezed by the hand of the operator, the pivotally mounted lever 41 is moved inwardly against the action of the spring 42, thereby causing the depression of the link 44 of the toggle 45, thus drawing the lower ends of the vertical tongs 47 together, which in turn closes the upper ends of the said tongs and, correspondingly, the most adjacent ends of the horizontal tongs 49. This action causes the closing of the inner ends of the horizontal tongs 49 to cause the inwardly extending links 51 to separate the bars 32 which are formed integrally with the hollow side castings 16. The cooling apparatus of the invention may then be placed over the end of the workpiece, such as a railroad rail. Release of the pivotally mounted lever 41 produces a reversal of the foregoing action, whereby the workpiece is embraced by the elements in the manner shown in Figure 2.

While I have shown and described certain specific embodiments of the present invention, it will be readily understood by those skilled in the art that I do not wish to be limited exactly thereto, since various modifications may be made without departing from the scope of the invention as defined in the appended claims.

I claim:

1. An apparatus for cooling the ends of heat-treated rails comprising a water-cooled jacket having a horizontal section adapted to lie against the top face of a rail and a vertical section adapted to lie against the end face of the rail, a pair of water-cooled jackets adapted to lie against the side faces of the rail head, a slotted connection on the top of said first-named jacket slidably mounting said second-named jackets on said first-named jacket, a spring biasing said second-named jackets toward each other, a linkage for spreading said second-named jackets, and a handle on said first-named jacket having a grip for operating said linkage.

2. An apparatus for cooling the ends of heat-treated rails comprising a water-cooled jacket having a horizontal section adapted to lie against the top face of a rail, a vertical section adapted to lie against the end face of the rail and a handle protruding from said vertical section, a pair of vertical water-cooled jackets adapted to lie against the side faces of the rail head, a slotted connection on the top of said first-named jacket slidably mounting said second-named jackets on said first-named jacket and constraining their movement to translational movement, a spring biasing said second-named jackets toward each other, a linkage for spreading said second-named jackets, and a grip on said handle for operating said linkage, actuation of said grip spreading said second-named jackets for receiving the rail head

and release of said grip automatically engaging said second-named jackets with the rail head.

3. An apparatus for cooling the ends of heat-treated rails comprising a water-cooled jacket having a horizontal section adapted to lie against the top face of a rail, an integral vertical section adapted to lie against the end face of the rail, and an integral handle protruding from said vertical section, a pair of vertical water-cooled jackets adapted to lie against the side faces of the rail head and having inwardly facing grooves receiving said first-named jacket, a slotted connection on the top of said first-named jacket slidably mounting said second-named jackets on said first-named jacket, said grooves and said slotted connection constraining movement of said second-named jackets to translational movement, a spring biasing said second-named jackets toward each other, a linkage for spreading said second-named jackets, and a grip on said handle for operating said linkage, actuation of said handle

spreading said second-named jackets for receiving the rail head and release of said grip automatically engaging said second-named jackets with the rail head, the spacing of said second-named jackets automatically accommodating itself to different widths of rail head.
